DESIGN FOR A BAFFLE ELEMENT FOR LIGHTING FIXTURES

Edward F. Sibbert, Brooklyn, N. Y., assignor to
S. H. Kress and Company, New York, N. Y., a
corporation of New York

Application July 1, 1937, Serial No. 70,203

Term of patent 14 years

To all whom it may concern:

Be it known that I, Edward F. Sibbert, a citizen of the United States and residing at Brooklyn, New York, have invented a new, original, and ornamental Design for a Baffle Element for Lighting Fixtures, of which the following is a specification, reference being had to the accompanying drawing, forming part thereof, and in which—

Fig. 1 is a plan view of the baffle element for lighting fixtures showing my new design, and

Fig. 2 is a transverse sectional view taken on line 2—2 of Fig. 1, looking in the direction of the arrows and drawn on a smaller scale.

The essential feature of my design resides in the arrangement of the baffle members as shown in Fig. 1 of the drawing.

This application is a continuation-in-part of my copending application, Serial No. D-60068, filed December 14, 1935.

I claim:

The ornamental design for a baffle element for lighting fixtures, substantially as shown and described.

EDWARD F. SIBBERT.
